UNITED STATES PATENT OFFICE.

EZEKIEL W. BULLARD, OF BARRE, AND CHARLES E. BULLARD, OF WORCESTER, MASSACHUSETTS.

BOX-OPENING TOOL.

SPECIFICATION forming part of Letters Patent No. 416,208, dated December 3, 1889.

Application filed January 24, 1889. Serial No. 297,386. (No model.)

To all whom it may concern:

Be it known that we, EZEKIEL W. BULLARD and CHARLES E. BULLARD, both citizens of the United States, the former residing at Barre and the latter residing at Worcester, in the county of Worcester and State of Massachusetts, have invented certain new and useful Improvements in Box-Opening Tools, of which the following, together with the accompanying drawings, is a specification sufficiently full, clear, and exact to enable persons skilled in the art to which this invention appertains to make and use the same.

15 The object of our present invention is to provide a convenient and efficient tool for the purposes specified, wherein the wedge-shaped entering-head or ripping-claw is connected with the handle-bar by an offsetting neck, which serves as a fulcrum-bearing upon the edge of the box and greatly facilitates the operation of ripping up the boards; also, to provide a box-opening tool having a ripping-claw, an offsetting neck, and a hammer-face arranged as hereinafter explained.

In the drawings, Figure 1 is a top view of our improved tool. Fig. 2 is a side view of the same. Fig. 3 is a perspective view illustrating the manner of its use, and Fig. 4. 30 shows a modification wherein the ripping-claw is made to stand at an angle in relation to the plane of the handle-bar and offsetting neck to permit of the tool being used against a flat surface.

35 In referring to parts, A denotes the handle-bar, and B the head or ripping-claw, which is made with a wedge-shaped outer end b, having a nail-drawing slit d, and is connected with the handle-bar by an offsetting neck C, 40 at right angle, or substantially so, to the handle and claw, which latter stand in the same direction, but out of line with each other, the offset of the neck C being slightly more than the thickness of ordinary boards, 45 or, say, about one inch, more or less.

The inner end f of the claw-head B is fitted to receive the blows of a hammer or maul for driving the wedge-shaped point b into the crevice between the boards.

50 The end of the handle-bar is best pro-

vided with a handle A², as shown, but may in any instance be made plain, if desired.

On the side of the bar A, opposite the offsetting neck, there is provided a hammer-face E, which permits of the tool being used 55 for driving nails or for knocking nails from the box-covers.

In the operation of the tool the wedge-shaped end b is driven into the crevice by striking on the head at f. Then when the box-cover I is started the tool is used as a lever, the offsetting neck resting on the edge of the box, as shown in Fig. 3, and serving as a fulcrum. Thus the leverage is thereby balanced, so that the lifting force is more 65 advantageously exerted, the power being applied more directly upward, while there is less tendency for the tool to roll over sideways than is the case with the ordinary straight form of tool. Consequently the work 70 of ripping open packing-cases, &c., can be performed with greater facility and dispatch, while there is less liability of injuring the covers and edges of the cases if it is desired to preserve them for repacking of goods. 75

In some cases the hammer-face may be omitted, if desired.

When the tool is designed for ripping carpentry-work—such as door and window casings, and for similar purpose—the tool can 80 be made with its head B standing somewhat at an oblique angle to the plane of the handle-bar A, as illustrated in Fig. 4, to allow of the tool being worked against a wall or flat surface in substantially the same plane with 85 the crevice into which the claw is to be driven.

We claim as our invention, to be secured by Letters Patent—

1. A box-opening tool composed of a lever or handle-bar A and a claw-head B, having a wedge-shaped end b projecting in the direction of the handle, but at offset position, and integrally joined thereto at its side by a lateral neck C, arranged at right angles in relation to the head and bar, substantially as and for the purpose set forth. 95

2. A box-opener or ripping-tool having its handle-bar A and head B laterally offset from each other and integrally connected by a transverse neck C, said head being formed 100

with a wedge-shaped end at *b*, and a nail-slit *d*, and a striker-seat at *f*, substantially as shown and described.

3. The within-described box-opening tool, consisting of the lever or handle-bar *A*, having the head *B* fitted with the bifurcated wedge-shaped end at *b*, and the striker-seat at *f*, integrally connected to the bar by the transversely offsetting neck *C*, and having in 10 continuation of said neck, at the opposite

side of the bar, the hammer-face *E*, all substantially as shown and described.

Witness our hands this 22d day of January, A. D. 1889.

EZEKIEL W. BULLARD.
